Concord, Mass. 01742

Filed Aug. 24, 1966, Ser. No. 3,572

Term of patent 14 years

(Cl. D29—17)

The figure on the drawing is a front elevational view of a flag showing my new design, the opposite side being substantially the same in appearance.

The essential features of the design reside in the portions shown in solid lines, the conventional printed matter being shown in broken lines.

I claim:

The ornamental design for a flag or similar article, as shown and described.
